UNITED STATES PATENT OFFICE.

JOHN F. MCCOY, DECEASED, BY MARY MCCOY, ADMINISTRATRIX, OF BROOKLYN, NEW YORK.

TRAIN-STOPPING TRIP OR OBSTACLE.

1,233,895.

Specification of Letters Patent. Patented July 17, 1917.

Original application filed October 1, 1914, Serial No. 864,403. Divided and this application filed January 16, 1917. Serial No. 142,586.

To all whom it may concern:

Be it known that JOHN F. MCCOY, now deceased, of whom the undersigned, MARY McCoy, who resides in the city of New York, borough of Brooklyn, in the county of Kings and State of New York, is the duly appointed administratrix, has invented a certain new and useful Improvement in Train-Stopping Trips or Obstacles, of which 10 the following is a full, clear, and exact description.

This application is a division of an application for United States Letters Patent filed by the said John F. McCoy, Number 15 864,403, October 1, 1914.

This invention relates to train stopping trips or obstacles adapted to be set up in the track by a trainman of a train that has been stopped, so as to protect such stopped 20 train from accident by a succeeding train colliding with it.

The invention has for its general objects to improve the construction of devices of this character so as to be reliable and efficient in use, comparatively simple and inexpensive to manufacture, and so designed that when it has performed its function it automatically moves to inoperative position so that the track will be clear for traffic.

30 A more specific object of the invention is the provision of a staff-like trip having hingedly connected sections pivoted on different centers in such a manner that these sections can be held together in upright position by means which can be destroyed by the burning of a time fuse or by the blow of a train-carried element, whereupon the sections automatically swing downwardly to an inoperative position.

40 Another object of the invention is the provision of a combined trip and signal having the characteristics above referred to in combination with means whereby the combined trip and signal can be positioned 45 in only one way in the track.

Another object is to provide a train-carried stopping device so designed as to operate to destroy an element which holds the two sections of the staff in upright position.

50 With such objects in view, and others which will appear as the description proceeds, the invention comprises various novel features of construction and arrangement of parts which will be set forth with par-

ticularity in the following description and 55 claims appended hereto.

In the accompanying drawings, which illustrate one embodiment of the invention and wherein similar characters of reference indicate corresponding parts in all the 60 views,

Figure 1 is a side view of a train-carried stopping device with a portion broken away and about to strike a roadside trip;

Fig. 2 is a front view of the said stopping 65 device;

Fig. 3 is a plan view;

Fig. 4 is a detail section on the line 4—4, Fig. 1;

Fig. 5 is an enlarged sectional view taken 70 on the plane indicated by the line 5—5, Fig. 1;

Fig. 6 is a plan view of a portion of the trip-holding socket;

Fig. 7 is an end view of the socket piece; 75

Fig. 8 is a side view, partly in section, of the trip;

Fig. 9 is a transverse section on the line 9—9, Fig. 8;

Fig. 10 is a detail side view of a portion 80 of the trip; and

Fig. 11 is a vertical section of the signal fuse.

Referring to the drawing, A designates a trip-operated train stopping device which 85 includes a valve or equivalent device 1 suitably carried by the train or car, whereby the propelling power can be cut off or the brakes set, or both, the device 1 being actuated by a rock shaft 2 carried by a suitable 90 part 3 of the locomotive or car, and on this rock shaft are oppositely extending arms 4 and 5 that are connected by links 6 and 7 with a pivoted trip-engaging element 8. This element is a frame of shallow V-shaped 95 form in side view and comprises a pair of forward bifurcations 9 and a pair of rearward bifurcations 10, there being inclined surfaces 11 at the center of the device 8 and between the bifurcations, each inclined surface serving to have a wiping action on the trip, whereby the element 8 will be swung from its normal position so as to operate through the links 6 and 7 to actuate the device 1. The device 8 is pivoted on a bracket 100 or hanger 12 to swing on a center 13, and the links 6 and 7 are connected at 14 and 15 with the element 8 at opposite sides of the 105

center 13. The opposed faces 16 of the bifurcations are formed with serrations 17 so as to cause the mutilation of a certain part of the trip, whereby the latter can, after 5 having performed its function, move to inoperative position.

The trip B is a device which will be carried by the train so that a trainman can set up the trip whenever it is necessary to protect a stopped train from a following train. 10 The trip device B is in the form of a staff which has a non-circular lower end 18 to fit in a correspondingly shaped socket 19 of a socket plate 20. The socket plates 20 are permanently positioned in the track at suitably spaced intervals, and preferably each socket plate rests on a tie 21 and is fastened thereto in any suitable manner, as, for instance, by spikes 22, Fig. 7, and by bolts 23 which pass 15 through eyes 24 at one end of the socket plate and through a track rail 25.

The upper part of the staff-like trip B is composed of two sections or members 26 and 27 which are connected by pivots 26^a and 25 27^a with the base 28 of the staff. The pivotal centers 26^a and 27^a are arranged at different levels so that the two sections 26 and 27 cannot swing in parallelism, and consequently, if the two sections are held together they will 30 remain in a vertical position against the action of their respective springs 29 and 30. These springs are mounted on the base 28 and bent to throw the sections 26 laterally from a vertical position, or to the left in Fig. 8. The sections 26 and 27 are held together by a mutilatable and fusible ring 31 applied to the upper end of the trip, and when this ring is destroyed the members 26 and 27 will move from a vertical operative 35 position to a lateral inoperative position. To assist in the proper mating of the members 26 and 27 one is provided with a longitudinal rib 32 and the other with a longitudinal groove 33 into which the rib fits, as 40 shown in Fig. 9. The ring 31 is adapted to be struck by the serrated surfaces 17 of the train-carried stop element 8, and the serrations destroy the ring so that the trip will move to inoperative position, but before the 45 members 26 and 27 of the trip can move to inoperative position they engage the inclined surface 11, whereby the stopping device is operated, and after the element passes the trip the members 26 and 27 swing in a direction transverse to the track on their pivots 26^a and 27^a, and assume an inoperative position.

If a visual signal is desired for day use, a flag 34 as indicated by dotted lines, Fig. 8, 60 can be held in a socket 35 on one of the members of the trip. For signaling by night a colored light fuse C may be applied to the trip, such fuse having its lower end 36 constructed to enter a socket 37 formed by making recesses in the members 26 and 27 of the

trip, the ring 31 having a mouth 38 for facilitating the entrance of the signal device C into the trip. The device C comprises a rod of suitable inflammable material 39 having a protective casing 40 and a protective cap 41. On the bottom of the fuse C is a conical hood 42 which is disposed over the fusible ring 31, so that the latter will not be melted by the hot residue of the burning fuse until the fuse is almost entirely burned up, when the ring 31 will be permitted to melt and allow the trip to move to inoperative position. It is to be understood that the fuse C will burn a predetermined length of time to enable a train to proceed far enough to be out of the danger zone of a succeeding train, and the fuse finally performs the function of rendering the trip inoperative, but if a succeeding train should proceed without heeding the fuse, the trip device will be operative to stop such train. The bottom of the fuse is so constructed that it will have direct contact with the ring 31, so that the inflammable material of the fuse will finally ignite for the purpose just mentioned.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described the invention, I claim as new and desire to secure by Letters Patent:

1. A signaling and tripping device mounted alongside of the track for indication of the condition of a block or track preceding a train, said tripping device being adapted to move into operative and inoperative positions and when disposed in an operative position to engage a train-carried, valve-throwing device for opening the valve and applying the brakes, said tripping device including a staff adapted to be supported in juxtaposition to the tracks and having a pair of sections having a coacting rib and recess, and means to secure said sections together in elevated positions and adapted upon being engaged with the valve throwing device to be mutilated to permit the sections to drop out of tripping position.

2. A signaling and tripping device mounted alongside of the track for indication of the condition of a block or track preceding a train, said tripping device being adapted to move into operative and inoperative positions and when disposed in an operative position to engage a train-carried stopping de-

- vice, said tripping device including a staff adapted to be supported in juxtaposition to the tracks and having a pair of sections having a coacting rib and recess, means to secure 5 said sections together in elevated positions and adapted upon being engaged with the stopping device to be mutilated to permit the sections to drop out of tripping position, and means tending to move said sections to 10 inoperative positions but permitting them to be disposed together and in alinement by means of the coacting rib and recess.
3. A signaling and tripping device mounted alongside of the track for indication of the 15 condition of a block or track preceding a train, and adapted to move into operative and inoperative positions and when disposed in an operative position to engage a train-carried stopping device, said tripping device including a staff adapted to be supported in juxtaposition to the tracks and having a pair of sections, and means to secure 20 said sections together in elevated positions and adapted upon being engaged with the valve throwing device to be mutilated to permit the sections to drop out of tripping position, said sections having coacting recesses in their upper ends to receive a 25 fuse.
- 30 4. A signaling and tripping device mounted alongside of the track for indication of the condition of a block or track preceding a train, and adapted to move into operative and inoperative positions and when disposed in an operative position to engage a train-carried stopping device, said tripping device including a staff adapted to be supported in juxtaposition to the tracks and having a 35 pair of sections and fusible means to secure said sections together in elevated positions and adapted upon being engaged with the stopping device to be mutilated to permit the sections to drop out of tripping position, said sections having coacting recesses in their upper ends forming a recess and having notches adjacent to the said fusible 40 means and a fuse fitting said recess and provided with a plate to normally protect the fusible means during the initial burning 45 of the fuse but adapted to permit the melting thereof after the fuse has burned a predetermined time to free the sections and permit them to swing to the positions aforesaid.
5. In a train stopping apparatus, sockets 55 mounted at spaced distances along a track and each being secured to the rails and having receiving portions of irregular contour, and a combined tripping and signaling device for application to said sockets in one 60 position, said tripping device being movable in one direction to an inoperative position whereby its engagement with the valve throwing device will be prevented and means destructible by contact with a train-carried 65 element for normally holding the device upright.
6. A combined signaling and tripping device mounted in juxtaposition to a track, said tripping device including sections 70 pivoted on different centers and adapted to be moved into operative and inoperative positions.
7. The combination of a roadside trip composed of upwardly extending members 75 mounted to swing laterally on different centers, means tending to throw the members laterally, and a destructible element engaged with the members to hold the same upright, with a train-carried stopping device having 80 means for destroying the said destructible element to permit the members to move laterally after they have actuated the stopping device.
8. A roadside trip comprising a staff having 85 upstanding members mounted to swing laterally on different centers, means tending to swing the members laterally, and a fusible element normally holding the members together in upstanding position, in combination with a fuse adapted to melt the element after the lapse of a predetermined interval of time, whereby the members move to inoperative position.
9. A roadside trip comprising a staff having 95 upstanding members mounted to swing laterally on different centers, means tending to swing the members laterally, and a fusible element normally holding the members together in upstanding position, in combination with a fuse adapted to be supported adjacent the members and in contact with the said element, and means on the fuse for preventing the melting of the element before the fuse has burned a predetermined period 100 of time.
- 105
